CLAIM

The ornamental design for an expansion trigger and holder assembly for a sampling system, as shown and described.

DESCRIPTION

FIG. 1 is a perspective view of an expansion trigger and holder assembly for a sampling system;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken line showing of the expansion triggers is for environmental purpose. The remaining broken lines depict portions of the expansion trigger and holder assembly for a sampling system that form no part of the claimed design. The broken lines form no part of the claimed design.
